FIG. 1 is a top front perspective view of a chassis for a video game console showing our new design.

FIG. 2 is a top plan view thereof.

FIG. 3 is a front elevational view thereof.

FIG. 4 is a right side elevational view thereof.

FIG. 5 is a left side elevational view thereof.

FIG. 6 is a rear elevational view thereof.

FIG. 7 is a bottom plan view thereof.

FIG. 8 is a top front perspective view of a second embodiment thereof.

FIG. 9 is a top plan view thereof.

FIG. 10 is a front elevational view thereof.

FIG. 11 is a right side elevational view thereof.

FIG. 12 is a left side elevational view thereof.

FIG. 13 is a rear elevational view thereof; and,

FIG. 14 is a bottom plan view thereof.

The broken lines represent portions of the chassis for a video game console that form no part of the claim.
